UNITED STATES PATENT OFFICE.

LEW ARNTZ AND BONNIE WALTERS, OF DES MOINES, IOWA.

DETACHABLE SHOE-HEEL PAD.

1,371,339.

Specification of Letters Patent. Patented Mar. 15, 1921.

Application filed January 6, 1920. Serial No. 349,823.

To all whom it may concern:

Be it known that we, LEW ARNTZ and BONNIE WALTERS, citizens of the United States, and residents of Des Moines, in the 5 county of Polk and State of Iowa, have invented a certain new and useful Detachable Shoe-Heel Pad, of which the following is a specification.

The object of our invention is to provide 10 a combination of a shoe heel with a detachable pad therefor with simple, durable and inexpensive means for removably mounting the pad on the heel in such manner that the pad can not accidentally be removed.

With these and other objects in view, our 15 invention consists in the construction, arrangement and combination of the various parts of the device, whereby the objects contemplated are attained, as hereinafter more 20 fully set forth, pointed out in our claims, and illustrated in the accompanying drawings, in which:

Figure 1 shows a vertical, sectional view through a heel and pad and fastening means 25 embodying our invention.

Fig. 2 shows a similar view showing the pad removed.

Fig. 3 shows a top or plan view of the pad illustrated in Figs. 1 and 2.

Fig. 4 shows a view similar to that shown 30 in Fig. 1, of a form in which our invention may be embodied.

Fig. 5 shows an inverted plan view of the plate on the bottom of the heel, illustrated 35 in Fig. 4; and.

Fig. 6 shows a side elevation of a shoe equipped with a removable pad embodying our invention.

It is well-known that especially in the 40 case of women's shoes, having comparatively slender heels, the heels wear off quickly and require frequent and expensive repairs. It is to provide a pad, which can be put on the heel by the user, that we have devised our 45 present device.

In the accompanying drawings, we have used the reference numeral 10 to indicate generally the heel of a shoe 11. Fastened to the bottom of the heel 10 by means of 50 screws 12 or other suitable means, is a metal plate 13, which is preferably provided at

its periphery with upwardly and downwardly extending short flanges 14 and 15.

The plate 13 is also formed with suitable openings 16 to receive the pins hereinafter 55 referred to. The heel 10 is provided with openings 17 to register with the openings 16.

The heel 10 is provided in the central portion of its under surface with a recess 18, and the plate 13 in the form of our invention shown in Figs. 1 and 2, is provided with a boss or thickened portion 19, which may be as shown, on the lower side of the plate 13.

The plate 13 and boss 19 are provided 65 with a screw threaded opening 20. We provide a shoe heel pad 21, preferably of leather and of suitable size and shape, which is relatively thin, and has on its upper surface a convex-concave metal plate 22, having its 70 concave surface upward, which plate is secured to the pad 21 by screws 23.

The plate 22 has upwardly projecting pins 24 designed to enter the holes 16 and 17 for holding the plate 22 against any rotary movement, when it is assembled on the heel 10.

In the plate 22 is an opening 25 to receive a screw bolt 27. The pad 21 is provided with an opening 28 of larger diameter than 80 the opening 25, to receive the head of the bolt 27.

In Fig. 4 we have shown the slightly modified form of our invention, in which the heel 10 is provided with a plate 13^a, similar to the plate 13, with the exception that the plate 13^a has a boss 19^a on its upper surface. In the form of the invention shown in Fig. 4, the pad 21 has a plate 22^a on its upper surface, similar to the plate 22, excepting that the plate 22^a has a screw-threaded boss or the like 26^a on its upper surface, through which the screw-threaded bolt 27 may pass. The under surface of the plate 13 is shown in Fig. 5.

In the practical installation and use of our improved detachable heel pad structure, the plate 13 is mounted on the heel 10. The plate 22 is of such size that its edges will rest within the flange 15.

When the form of invention shown in Figs. 1 and 2 is employed, the pad is placed

in position with the edges of the plate 22 resting against the plate 13 adjacent to the flange 15, and the screw-bolt 27 is then inserted through the central opening in the lower plate and is screwed into the upper metal plate.

The shape of the plate 22 and the thickness of the boss 19 are such that when the plates 13 and 22 are placed together, the 10 boss 19 does not touch the center of the plate 22.

As the parts are drawn together by the screw-bolt 27, the central portion of the plate 22 is sprung for snugly drawing it toward the boss 19 for forcing the edges 15 of the plate 22 outwardly into snug engagement with the flange 15. The pins 24 enter the openings 16 and 17 with sufficient play to permit the edges of the plate 22 to be pressed against the flange 15.

20 Similarly when the form of invention shown in Fig. 4 is used, the plate 22^a is placed adjacent to the plate 13^a with the pins 24 extended into the openings 17 and the screw-threaded bolt 27 is screwed into the 25 plate 22^a until it reaches and enters the openings 20. It is then screwed into the openings of both plates and will finally draw the plates tightly together, until the boss 26^a is drawn against or almost against 30 the plate 13^a and the edges of the plate 22^a engage the flange 15.

It will be noted that in the form of the invention shown in Fig. 4, the boss 26^a on the upper surface of the plate 13^a is threaded, while the plate 13^a itself is not threaded.

35 While it will be readily seen that our invention may be embodied in a structure having a great variety of differences in details, there are certain important features of our 40 device to which we desire to especially call attention.

There should be a plate secured to the bottom of the shoe heel, which plate furnishes a proper bearing and gripping member for the screw-bolt 27 or its equivalent, and also 45 furnishes a means for holding the pins 24 or their equivalents in position for preventing any twisting of one of the plates with relation to the other.

50 This plate on the shoe heel also furnishes a protection in the form of the flange 15 for the edge of the plate on the upper surface of the heel pad.

There must also be the heel pad having 55 on its upper surface a plate. One of the plates must be concavo-convex, with its concave face adjacent to the other plate. We have shown the pad having on its upper surface the concavo-convex plate with its concave surface up, so that when the center of 60 the plate on the heel pad is drawn toward the heel of the shoe by the action of the screw-bolt 27, the outer edge of the plate of the pad will engage the flange 15 of the 65 shoe heel and when these parts are fastened

together, they will be held against any twisting movement both by the pins 24 and by the yielding frictional engagement of the two plates with each other. The use of the spring or resiliency of the plate on the 70 pad in the manner just described, holds said plate under tension and provides a spring lock in connection with the bolt 27 for preventing any loosening of the bolt 27 which might otherwise result in loosening the pad. 75

Thus it appears that on account of the shape of the plate on the heel pad, with its concavo-convex form, as illustrated, the bolt 27 may be employed to spring the central portion of the arch formed by the plate on 80 the heel pad, so as to form what may be called a circular brace held under tension, which provides a spring lock for the bolt. It may be mentioned in this connection that the central portion of the heel pad plate is 85 shaped after the surface of a sphere so that the curvature in all directions running from the central opening in the heel pad plate is the same.

It will readily be seen that many changes 90 in details of structure may be made in our device, which may be embodied in our invention, and it is our intention to cover by our claims any changes in structure which may be reasonably included within their scope. 95

We claim as our invention:

1. In a device of the class described, the combination of a shoe having a heel, with a plate on said heel secured thereto, having a peripheral downwardly extending 100 flange, a pad having a concavo-convex plate secured to its upper surface, and means for gripping said plates together for holding the lower plate under tension.

2. In a device of the class described, the 105 combination of a shoe having a heel, with a plate on said heel secured thereto, having a peripheral downwardly extending flange, a pad having a concavo-convex plate secured to its upper surface, and means for 110 gripping said plates together for holding the lower plate under tension, one of said plates having openings, and the other having pins adapted to enter said openings.

3. In a device of the class described, the 115 combination of a shoe having a heel, with a plate secured to said heel, a pad, a plate secured to said pad, one of said plates being concavo-convex, and means for gripping said plates together for holding the concavo-convex plate under yielding tension.

4. In a device of the class described, the combination of a shoe having a heel, with a metal plate secured to said heel, a pad, a concavo-convex plate secured to said pad, 125 and means for gripping said plates together for holding the concave plate under tension, one of said plates having a hole and the other having a pin arranged to enter said hole,

5. In a device of the class described, the combination of a shoe having a heel, a plate secured to the bottom of said heel, having upwardly and downwardly extending flanges at its edges, a paid, a concavo-convex plate on the upper surface of said pad secured thereto, said plates having coacting holes and pins, and a screw device adapted for locking said plates together with the lower plate under tension. 10

Des Moines, Iowa, November 22, 1919.

LEW ARNTZ.
BONNIE WALTERS.
